LOOSE LEAF BINDER

Paul O. Unger, Elmhurst, Ill., assignor to Wilson-Jones Company, Chicago, Ill., a corporation of Massachusetts

Application October 14, 1935, Serial No. 44,830

7 Claims. (Cl. 129—13)

This invention relates to loose leaf binders particularly adapted for use in connection with machine posting. In machine posting devices of the front feed type it is very desirable to use sheets having an unbroken top edge. This invention is particularly concerned with means for retaining sheets of this type in a binder in such a manner that the sheets may be handled very rapidly during the posting operations.

It is an object of this invention to provide a sheet retaining post that may be readily inserted into a loose leaf binder to retain the sheets therein and may be readily removed so as not to impede the rapid removal and replacement of the sheets during the posting operations. It is a further object of this invention to provide simple and efficient means in the binder to securely retain the post in sheet retaining position and yet permit easy removal therefrom. Other objects of this invention will become apparent upon reading the following description taken in conjunction with the accompanying drawing, in which

Figure 1 is a cross sectional view taken substantially on the line I—I of Figure 2 through the back of a binder embodying this invention;

Figure 2 is a fragmentary top plan view of the binder with parts broken away to facilitate illustration of the structure;

Figure 3 is a fragmentary cross sectional view showing the means for removing the sheet retaining post;

Figure 4 is a detail perspective view of the sheet retaining post; and

Figure 5 is a fragmentary perspective view of the means for holding the sheet retaining post in the binder.

In the drawing, the reference numerals 2 and 3 indicate a pair of clamping or back members which are movable transversely relative to each other. The back members 2 and 3 each are provided with a plate member, 2' and 3' respectively, which may be integral therewith, and which extend at an angle to the back members. Cover members 4 are hinged to the plate members 2', 3', as indicated at 5. The ends of the back member 2 are bent over, as indicated at 6, to form guide channels in which the ends of the back member 3 are moved. Interengaging tongues 7 and 8 on the bent over portion 6 and the back member 3, respectively, prevent separation of the back members.

A channel shaped member 9 is rigidly secured to the plate member 3' to form a tubular compartment 10. A channel shaped member 11 is rigidly secured to the plate member 2' to form a

tubular compartment 12. The compartments 10 and 12 extend the length of the binder back and are closed at their ends by means of end caps 13 of felt, fiber, or any other material adapted to prevent the binder from marring any finished surface on which it may be handled. The back members 2 and 3 are connected by a pair of posts 14 each of which consists of a tubular section 15 rigidly secured to the plate member 2', as shown at 16, and a second tubular section 17 secured to the plate member 3', as shown at 18, and adapted to telescope into the section 15. A coiled spring 19 is contained within the telescopic post 14, and normally tends to expand to separate the back members 2 and 3.

The back members 2 and 3 are also connected by a pair of telescopic locking posts 20. Each locking post 20 consists of a tubular section 21 rigidly secured to the plate member 3', as shown at 22, and a solid section 23 secured to the plate member 2' by means of a screw 24 and adapted to telescope into the tubular section 21. Each section 23 is provided near its unsecured end with a conical portion 25 providing a space 26 in which a plurality of gravity operated balls 27 is contained. The space 26 is closed at one end by the body portion of the section 23 and at the other end by a flange 28 fitting snugly in the section 21. The unsecured end of the section 21 is provided with an inturned flange 29 adapted to engage the flange 28 to prevent separation of the sections 21 and 23. When the binder is in the position of Figure 1, any attempt to move the back members apart will wedge the balls 27 into the small end of the space 26 and thereby prevent such movement. When the binder is reversed the balls 27 roll to the large end of the space 26 and the back members 2 and 3 may be moved apart until the tongues 7 and 8 interengage.

The posts 14 and 20 are arranged adjacent the ends of the binder, as indicated in Figure 2, so as to permit the insertion of sheets 30 therebetween. The posts 14 and 20 form a guide means for aligning the sheets 30 as they are inserted in the binder. The sheets 30 are provided with one or more apertures 31 through which sheet retaining posts 32 may be inserted.

Each sheet retaining post 32 consists of a solid section 33 adapted to telescope into a tubular section 34. A coiled spring 35 positioned within the tubular section exerts a constant force tending to move the sections 33 and 34 out of telescoping relationship. A flange 36 rigidly secured to the section 33 and a restricted outlet 37 on the section 34 interengage to prevent complete

separation of the sections of the sheet retaining post 32. The section 34 is provided with an enlarged head 38 and has a threaded aperture 39 therein. A key 40 having a threaded end 41 is adapted to be screwed into the aperture 39 to rotate the section 34 and to press it inwardly against the action of the spring 35. The section 34 is also provided with a pin 42 having a pair of laterally projecting ends adjacent the headed end 38.

The plate member 2' and the channel shaped member 11 are apertured in registration with each other, as indicated at 43 and 44, respectively, to allow insertion of the sheet retaining posts 32. The apertures 43 are just large enough to permit insertion of the tubular portions 34, but the apertures 44 are large enough to receive the headed ends 38 of the posts. The plate member 3' is apertured and embossed, as indicated at 45, to receive the tip end of the section 33, but the aperture is not large enough to allow the section 33 to pass therethrough.

The plate member 2' has secured thereto a plurality of members 46 each of which is apertured, as indicated at 47, in registration with the apertures 43. The member 46 is embossed to provide a circular flange 48 surrounding the aperture 47. The flange 48 provides a space 49 between the plates 2' and 46 adjacent the apertures 43 and 47. The space 49 is large enough to receive the projecting ends of pin 42. The flange 48 is provided with a pair of recesses 50 through which the pin 42 may be inserted into the space 49. After the pin 42 has passed through the recesses 50 a slight rotation of the section 34 will bring the pin 42 under the flange 48 whereby the sheet retaining post may be held in position.

The flange 48 is provided with a pair of embossments 51. When the section 34 is rotated a sufficient distance to bring the pin 42 into alignment with the embossments 51, the spring 35 urges the pin 42 into the embossments. The embossments are deep enough so that the key 40 may be easily unscrewed from the aperture 39 without moving the pin 42 out of the embossments. When it is desired to remove the posts 32 from the binder the key 40 is screwed into the aperture 39 all the way, and then continued rotation in the same direction will force the pin 42 out of the embossments 51 and into alignment with the recesses 50 at which time the spring 35 will force the post 32 out of its secured position.

Although I have shown a binder equipped with two sheet retaining posts it will be obvious that the number may be varied in accordance with the size of the sheets and the particular desires of the user. Inasmuch as many other details may be modified or changed without departing from the spirit or scope of my invention it will be understood that the description thereof is intended to be illustrative, rather than restrictive. Accordingly, I do not desire to be restricted to the exact construction described, except as limited by the appended claims.

I claim:

1. In a loose leaf binder, an apertured plate member, a flanged member secured to said plate member with its flange surrounding the aperture of said plate member and spaced a slight distance therefrom, and a headed post provided with a projection adjacent the headed end thereof, said post being insertable through said aperture to a point where said headed end contacts

against said flange, said flange being notched to permit passage of said projection.

2. In a loose leaf binder, a plate member, a flanged member secured to said plate member with its flange spaced therefrom, a post comprising a pair of spring pressed telescoping sections, a projection on one of said sections adjacent one end thereof, said projection being adapted to be received between said plate member and said flange to hold said post in said binder, and means on said flange adapted to cooperate with said projection to prevent accidental displacement of said post.

3. In a loose leaf binder, a plate member, a flanged member secured to said plate member with its flange spaced therefrom, and a headed post provided with a projection below the head of said post, said projection being adapted to be positioned between said plate member and said flange.

4. In a loose leaf binder, a plate member, a flanged member secured to said plate member with its flange spaced therefrom, a post comprising a pair of spring pressed telescoping sections, and a projection on one of said sections, said flange being notched to permit positioning of said projection between said flange and said plate member.

5. In a loose leaf binder, a plate member, a flanged member secured to said plate member with its flange spaced therefrom, a post, a projection adjacent one end of said post, said flange being notched to permit positioning of said projection between said flange and said plate member, said flange having an embossment spaced from said notch, means to rotate said post to position said projection into registration with said embossment, and means to force said projection into said embossment to retain said post in said binder against accidental displacement.

6. In a loose leaf binder, a plate member, a flange spaced from said plate member, a post, a projection adjacent one end of said post, said flange being notched to permit positioning of said projection between said flange and said plate member, said flange having an embossment spaced from said notch, means to rotate said post to position said projection into registration with said embossment, and a spring to force said projection into said embossment to retain said post in said binder against accidental displacement, said means being adapted to move said projection out of said embossment against the action of said spring to remove said post from the binder.

7. In a loose leaf binder, a pair of parallel apertured members spaced apart with their apertures in registration, a post insertable through said apertures, a projection adjacent one end of said post, one of said members being provided with a notch, said projection being insertable through said notch to position said projection between said members, an embossment on one of said members out of registration with said notch, means to rotate said post in one direction to position said projection into registration with said embossment, and means to force said projection into said embossment to retain said post in the binder against accidental displacement, said first mentioned means being operable to rotate said post farther in the same direction to position said projection into registration with said notch to permit removal of said post from the binder.
